COMBINED PAINT CAN OPENER AND PAIL HOOK

Leonard Howard, West Orange, N. J.

Application July 13, 1955, Serial No. 36,960

Term of patent 14 years

(Cl. D17—12)

Fig. 1 is a perspective view of a combined paint can opener and pail hook showing my new design; and

Fig. 2 is a front elevational view thereof; and

Fig. 3 is a side elevation of Fig. 2.

I claim:

The ornamental design for a combined paint can opener and pail hook, substantially as shown.
